UNITED STATES PATENT OFFICE.

LORNE A. GRIFFIN, OF EVANSTON, ILLINOIS, ASSIGNOR TO AMERICAN STEAM CONVEYOR CORPORATION, OF CHICAGO, ILLINOIS, A CORPORATION OF NEW YORK.

CONVEYER-CONDUIT.

1,342,167.

Specification of Letters Patent.

Patented June 1, 1920.

Application filed September 18, 1918. Serial No. 254,543.

To all whom it may concern:

Be it known that I, LORNE A. GRIFFIN, a citizen of the United States, residing at Evanston, in the county of Cook and State 5 of Illinois, have invented certain new and useful Improvements in Conveyer-Conduits, of which the following is a full, clear, concise, and exact description, reference being had to the accompanying drawings, forming 10 a part of this specification.

This invention relates to improvements in conveyer conduits, and is especially concerned with means for moistening the fine particles of ashes or dust, as they are being 15 driven through conduits forming part of an ash conveyer system, or any other system in which it is desired to produce agglomeration of these fine particles of dust, to prevent the dust from escaping from the tank 20 or receptacle into which the ashes or other material is discharged from the conveyer conduit.

The objects of my present invention are:—

25 First, to provide means for thoroughly wetting or moistening the dust in conveyer conduits which will require a minimum amount of water.

Second, to provide means of the character 30 described which may be easily and quickly inserted at any desired point in a conveyer conduit.

Third, to provide means of the character described in which there are no portions of 35 the spraying means projecting into the conveyer conduit to form obstructions to the material passing through the conduit.

Fourth, to provide means for thoroughly 40 and completely moistening all of the dust passing through the conveyer conduit, which comprises but a single spray nozzle or jet, positioned to discharge its spray through the wall of the conduit, the spray nozzle being of such construction as to provide a low 45 conical spray substantially filling the conduit from one side to the other so as to moisten all particles of dust passing therethrough.

Further objects and adaptabilities will 50 appear as the description progresses, reference being had to the accompanying drawings in which.

Figure 1 is an end elevation of my improved moistening device;

Fig. 2 is a longitudinal section there- 55 through taken on line 2—2 of Fig 1;

Fig. 3 is an end elevation partially in transverse section, showing the spray nozzle in position, and a means for securing it in its operative position; and 60

Fig. 4 is a longitudinal section through the spray nozzle, which I prefer to employ for my purpose.

Heretofore means have been provided for moistening the dust in ash conveyer conduits and other similar conveying systems which comprised a plurality of spray jets arranged about the periphery of the conduit, and arranged in such a manner as to discharge their jets across each other so as 70 to form a complete screen or spray of water across the conveyer conduit in order to intercept and moisten all the particles of dust. These jets have usually been eight in number and all substantially one-eighth 75 inch cross section operating under a head of from 12 to 15 feet.

Where spraying devices of the above mentioned type have been used, the quantity of water discharged into the ashes has been 80 considerable, and the weight of the ashes has been correspondingly increased, making it not only difficult to handle the ashes on account of their weight, but also causing difficulty in cold weather by reason of the 85 fact that due to this excessive amount of water the ashes became frozen into a solid mass which was difficult to remove from the receptacles into which they were discharged.

By employing a jet capable of producing 90 a spray extending substantially across the conveyer conduit, I am enabled to reduce the amount of water used to substantially one-eighth of that which has heretofore been found necessary, and to correspondingly reduce 95 the weight of the ashes and the difficulties heretofore experienced on account of the excessive amount of water absorbed by the ashes. By reason of the fact that I employ a nozzle which produces a substantially conical spray, the ashes and dust pass through a dense screen of water spray, and thorough moistening of the dust is thereby insured.

Referring to the drawings, reference 105 character 5 indicates a short section of conveyer conduit having the bolting flanges 6 at each end thereof. At spaced intervals

the wall of the conduit is provided with radially extending bosses 7, which are formed integrally with the flanges 6, and are provided with openings 8 for receiving bolts 5 for connecting this short section with the flanges on the adjacent ends of the conduit sections forming the conveyer conduit.

Another boss 9 extends outwardly from the wall of the conduit, between two of the 10 bosses 7, as shown in Figs. 1 and 3, and is provided with a bore 10, which discharges through the apex of the conical bore 11, formed in the inner side or wall of the conduit 5. The upper end of the boss 9 is provided with a pair of oppositely extending lugs 12, having the slots 13 formed therein. A cover plate 14 is secured to the outer end of the boss 7 by means of the bolts 15 which extend through suitable holes in the cover 20 plate, and through the slots 13 of the lugs 12. The cover plate 14 is provided with a central screw-threaded opening for receiving the screw-threaded end of the short pipe section 16.

Secured to the lower end of the pipe 16 by 25 means of a union 17 is a spray nozzle indicated as a whole by the reference character 18. This spray nozzle comprises an outer member 19, having inwardly converging 30 walls 20 adjacent the discharge orifice 21. Located in the bore of the member 19 is a member provided with a plurality of spiral channels 22, and a central bore 23. This nozzle produces a conical spray, which completely transversely fills the conveyer conduit with a dense spray through which the dust must pass.

The nozzle 18 is located so that its discharge orifice is positioned at substantially 40 the apex of the conical bore 11, and so that the spray from the nozzle is discharged substantially parallel with the walls of the bore 11, but not in contact therewith. The walls of the bore 11 may, of course, be given 45 any inclination desired so as to permit the spray to cover as large a section of the conduit as may be desired.

While I have described the details of the construction of the spray nozzle which I 50 prefer to employ, it is to be understood that these details form no part of my present invention, and that any nozzle giving a similar spray of such a character that it will extend entirely across the conveyer conduit 55 may be employed.

It is of course to be understood that my invention is capable of other adaptations and modifications within the scope of the appended claims.

Having thus described my invention, what I claim is:—

1. The combination with a conduit section having a bolting flange at each end and a boss extending radially between said flanges, the wall of said section being pro-

vided with a conical inwardly opening bore, and said boss being provided with a bore opening into said first named bore at the apex thereof, of a spray nozzle for producing a conical spray positioned in the bore 70 in said boss with its discharge end at substantially the apex of said conical bore, and means for holding said nozzle in said position comprising a cover plate for sealing the bore in said boss.

2. The combination with a conduit section having a boss extending radially from the walls thereof, the wall of said section being provided with a conical inwardly opening bore, and said boss being provided with a bore 80 opening into said first named bore at the apex thereof, of a spray nozzle for producing a conical spray positioned in the bore in said boss with its discharge end at substantially the apex of said conical bore, and 85 means for holding said nozzle in said position comprising a cover plate for sealing the bore in said boss.

3. The combination with a conduit section having a boss extending from the walls 90 thereof, the wall of said section being provided with a conical inwardly opening bore, and said boss being provided with a bore opening into said first named bore at the apex thereof, of a spray nozzle for producing a conical spray positioned in the bore in 95 said boss with its discharge end at substantially the apex of said conical bore, and means for holding said nozzle in said position.

4. The combination with a conduit section having a boss extending from the walls thereof, the wall of said section being provided with a conical inwardly opening bore, and said boss being provided with a bore 100 opening into said first named bore at the apex thereof, and a spray nozzle for producing a conical spray positioned in the bore in said boss with its discharge end at substantially the apex of said conical bore.

5. The combination with a conduit section having a conical bore extending through one wall thereof of a nozzle for producing a conical spray, the said nozzle being positioned to discharge its spray through said 115 conical bore into said conduit.

6. The combination with a conduit section having an unthreaded opening extending through the wall thereof, a closure plate for the outer end of said opening, means for securing said closure plate to said conduit section, together with a nozzle extending through said closure plate and threaded therein and extending freely into the opening aforesaid, whereby said nozzle is 120 adapted to discharge into the interior of said conduit section.

7. The combination with a conduit section having an unthreaded opening extending through the wall thereof, a nozzle extending 130

freely into said opening, a nozzle support with which said nozzle has threaded engagement, and means for holding said nozzle support in fixed relation to said conduit 5 section.

8. The combination with a conduit section having an unthreaded opening extending through the wall thereof, a nozzle projecting freely into said opening and discharging 10 into the conduit, a support by which said

nozzle is carried, and means for securing said support in fixed relation to said conduit section.

In witness whereof, I hereunto subscribe my name this 12th day of September, A. D. 15 1918.

LORNE A. GRIFFIN.
